Patented July 2, 1918.

2 SHEETS—SHEET 2.

UNITED STATES PATENT OFFICE.

JOHN G. SHODRON, OF MILWAUKEE, WISCONSIN, ASSIGNOR TO JAMES MANUFACTURING COMPANY, OF FORT ATKINSON, WISCONSIN, A CORPORATION OF WISCONSIN.

BARN-VENTILATOR.

1,270,879.

Specification of Letters Patent.

Patented July 2, 1918.

Application filed September 13, 1913. Serial No. 789,646.

To all whom it may concern:

Be it known that I, JOHN G. SHODRON, a citizen of the United States, residing at Milwaukee, county of Milwaukee, and State 5 of Wisconsin, have invented new and useful Improvements in Barn-Ventilators, of which the following is a specification.

My invention relates to improvements in barn ventilators and it pertains to that class 10 which are adapted to be used with barns having a lower compartment for cattle and other stock and an upper compartment for storing hay, grain and other feed. One of the primary objects of my invention is to 15 provide more efficient means for properly ventilating each of said compartments independently of the other. In other words I provide a stationary cupola having outwardly and downwardly inclined slats or louvers 20 between which air is free to escape from the upper compartment and a revoluble wind controlled ventilator supported from such cupola and connected through air ducts with the stables or lower compartments of the 25 barn through which ducts such compartments are ventilated.

My invention is further explained by reference to the accompanying drawings in which—

30 Figure 1 represents a vertical section of the barn provided with my improved ventilating system.

Fig. 2 is a vertical section of that part of the ventilator located above the roof of the 35 barn.

Fig. 3 is a detailed view showing a vertical section of a portion of the revoluble ventilator and a device for supporting the same.

40 Fig. 4 is also a detailed view part in section showing a device for detachably connecting a revoluble sleeve with the stationary part of the ventilator.

Fig. 5 is a horizontal section drawn on 45 line $x-x$ of Fig. 2.

Like parts are identified by the same reference numerals throughout the several views.

1 represents the lower compartments of the barn which is used for stabling cattle 50 and other stock. 2 is the upper compartment used for storing hay, grain, etc. 3 is a cupola of ordinary construction which is rigidly affixed to the roof 4 of the barn and is provided with a plurality of slats or 55 louvers 5 between which the air is free to

pass from the upper compartment 2 to the exterior. It is a well known fact that the motive power for maintaining a continuous current of air from the interior to the exterior of a barn is produced by the difference in temperature between the air in the interior and exterior. The air on the inside of the barn being warmer than that on the outside rises and passes out between the slats or louvers 5. This movement is also assisted 60 by the suction of the wind blowing across the top of the out take ducts, substantially as a chimney has a stronger draft when the wind is blowing hard than when the air is at rest.

What has been stated as to the action of the air escaping from the upper compartment 2 is also true as to the action of the air passing from the lower compartment 1. The air in the lower compartment is raised to a 70 higher temperature by the presence of the stock therein when it passes up through one or more ducts 6 to the central duct 7 when it passes from thence into the revoluble dome 8 and from thence into the exterior air 75 through the outlet opening 9. The dome 8 is revolvably supported from the upper end of the shaft 26 and said dome is adapted to revolve by the action of the wind the same being operated by the vane 11 and shaft 12. 80 The dome 8 is provided with a tapered chamber 13 which converges from the inlet end 14 to the outlet end 15. The larger inlet end 14 is retained toward the wind by the action of the vane 11 operating through the 85 shaft 12. It will be obvious that as wind passes through the chamber 13 its velocity is increased as it approaches the outlet end. The increase in velocity being due to the fact that all the air that enters the inlet end in a given period of time is forced through the outlet end at a greater speed in proportion as the outlet end is smaller than the inlet end, whereby the air is caused to escape from the chamber 13 at a higher velocity. 90

The air thus escaping from the chamber 13 at a high velocity has a tendency to create a strong suction which exerts a powerful pull on the air in the ducts 6 and 7 which communicate from the lower chamber 1 to 105 the revoluble dome 8. The inlet end of the tapered chamber 13 is provided with a screen 16 which prevents birds, dust and other refuse matters from entering such chamber, while the dome at the opposite end of said 110

chamber is provided with a screen 17 which also serves to exclude birds, dust and other refuse matter from the dome 8. 18 is a storm band which is rigidly supported from the duct 7 by a plurality of brackets 19. The brackets 19 are secured at one end to the storm band by rivets 20 and at their other ends to the duct 7 by a plurality of rivets 21. 22 and 23 are annular flanges or so-called skirts which are respectively connected at their upper ends to the duct 7 by a plurality of rivets in the ordinary manner. The annular flanges or skirts 22 and 23 diverge downwardly and outwardly and they together with the band 18 coöperate to protect the ventilator from injurious effect of the elements while the skirts aid in accelerating the circulation or escape of the air from the barn. The duct 7 together with the ventilator connected therewith are supported from the top of the cupola 3 by the inclosing walls 24, which walls are preferably formed of heavy galvanized sheet metal. The revolving dome 8 is supported from the duct 7 through the radial arms 25, vertical spindle 26 and a plurality of inclined rods 27. The arms 25 are supported at their outer ends from the ducts 7 and are connected therewith through rivets or in any convenient manner. The spindle 26 is connected near its center with the sleeve 28, while the upper ends of the rods 27 are connected with said sleeve 28 through the lugs 29 and bolts 30. The revoluble dome 8 is provided with a hollow central shaft 31 which shaft is rigidly connected at its lower end with the walls of said dome through the bracket 32 and a plurality of bolts 33, whereby said revoluble dome and central shaft 31 are adapted to revolve together. The upper end of the hollow shaft 31 is connected with the apex of the dome 8 through the central member 34. The member 34 is provided with a conical seat 35 for the reception of the tapered upper end of the stationary spindle 26. The stationary spindle 26 is rigidly affixed near its center to the sleeve 28, whereby it is obvious that said dome is free to turn on said supporting spindle with a minimum resistance, and whereby the mouth or larger open end of the chamber 13 is always retained in the direction of the wind and whereby a strong upward current of air is induced through the duct 7 by the passage of air through the chamber 13 as previously described.

To facilitate removing the dome 8 from the stationary pass of the upper ventilator, I have provided the lower end of the hollow shaft 31 with an annular collar 37, which collar 37 is in turn provided with an inward projecting lug 38 which is adapted to engage the annular beads 39 and 40 formed on the sleeve 28. It will be understood that when the hollow shaft 31 is in the position

shown in Fig. 4 the inwardly projecting lug 38 is free to pass the bead 39 until it is brought in contact with the bead 40. When this is done the hollow shaft 31 is turned a half revolution, whereby the inward projecting lug 38 will be brought in alinement with a groove 41 in said bead 40 when the hollow shaft 31 together with the dome 8 is free to be removed from the ventilator. 70

In replacing the ventilator the hollow shaft 31 is so turned as to bring the inward projecting lug 38 in alinement with the groove 41 when the hollow shaft 31 is lowered a short distance and until the inward projecting lug 38 is brought in contact with the bead 39 when said hollow shaft 31 is revolved again a half revolution whereby it is brought to the position shown in Fig. 4, when it is again lowered until the inward projecting lug 38 is free to pass the groove 85 formed in the flange 39 whereby the dome 8 is brought to its normal position for use. 90

Having thus described my invention what I claim as new and desire to secure by Letters Patent is:

1. The combination with a barn having a plurality of compartments, of a stationary ventilator connected with one of said barn compartments, a wind actuated revoluble aspirating ventilator, and a ventilating duct 95 leading thereto from one of the other barn compartments through the stationary ventilator.

2. The combination with a barn provided with a stable, of a stationary ventilator 100 adapted for delivery of air from that portion of the barn exterior to the stable, and a duct leading from said stable through said ventilator.

3. The combination with a barn provided 105 with a stable, of a stationary ventilator adapted for delivery of air from that portion of the barn exterior to the stable, a duct leading from said stable through said ventilator, and means for utilizing wind 110 pressure to accelerate the flow of air through said duct.

4. The combination with a barn comprising a compartment for live stock and another compartment for fodder, of a stationary ventilator rigidly affixed to the roof of the barn and having open communication with the fodder compartment of such barn, and a wind actuated revoluble aspirating ventilator supported from said stationary 115 ventilator and communicating with the stock compartment of said barn through said stationary ventilator.

5. The combination with a barn comprising a lower compartment for live stock and an upper compartment for fodder, of a stationary ventilator rigidly affixed to the roof of the barn, and having direct open communication with the upper compartment of such barn, and a wind actuated revoluble 130

- aspirating ventilator supported from said stationary ventilator, a plurality of ducts having open communication between said lower compartment and said revoluble 5 ventilator through said stationary ventilator, whereby heat from said lower compartment will accelerate the flow of air through said stationary ventilator.
6. The combination with a barn comprising a lower compartment for live stock and an upper compartment for fodder, of a stationary ventilator rigidly affixed to the roof of the barn and having direct open communication with the upper compartment of 10 such barn, a revoluble ventilator comprising a hood and a tapered chamber centrally located in said hood, supported from, and passing through said stationary ventilator, and means connected with said revoluble 15 ventilator for actuating the same by the shifting currents of wind, whereby the wider end of said tapered chamber is retained in the direction from which the wind is blowing.
- 20 7. The combination with a barn comprising a lower compartment for live stock and an upper compartment for fodder, of a stationary ventilator rigidly affixed to the roof of the barn and having direct open communication with the upper compartment of such barn, a revoluble ventilator supported from said stationary ventilator, a plurality of ducts having open communication between said lower compartment and said 25 revoluble ventilator through said stationary ventilator, a stationary storm band rigidly supported from the duct leading to said revoluble ventilator, the upper side of said storm band extending slightly above the 30 lower side of said revoluble ventilator, and means connected with said revoluble ventilator for actuating the same by the shifting currents of wind.
- 35 8. A ventilator, including a revoluble dome provided with a bottom inlet and also having lateral inlet and outlet openings, an open ended aspirating member extending transversely from the inlet side of said revoluble dome in the direction of the outlet, and provided with converging walls 40 adapted to concentrate air delivered through said passage under pressure of the wind, and
- a wind actuated vane operatively connected with and adapted to rotate the revoluble dome to positions with the lateral inlet on the windward side, whereby the movement of air through said passage under wind pressure will exert an aspirating effect at the outlet, in combination with a dome supporting ventilating duct communicating 45 with the bottom inlet of the dome, and an upwardly projecting spindle extending into the dome, and a shaft sleeve carried by the dome and adapted to receive said spindle, whereby the dome is supported revolubly 50 on said spindle.
- 55 9. In a device of the described class, the combination with a dome, and means for revolubly supporting the same above a stationary duct, of an aspirating member located in said revoluble dome having converging walls extending past the vertical center of said dome, and a vane connected with said revoluble dome adapted to retain the inlet end of said aspirating member toward the wind, whereby the movement of the air through said aspirating member will increase the flow of air through said stationary duct.
- 60 10. A ventilator including a revoluble dome provided with a bottom inlet, and also having lateral inlet and outlet openings, an open ended aspirating member extending transversely from the inlet side of said dome in the direction of the outlet, and provided with converging walls adapted to concentrate air delivered through said passage under pressure of the wind, a wind actuated vane connected with the dome, a ventilating duct leading to the bottom inlet 65 of the dome and provided with a centrally disposed spindle upon which the dome is revolubly mounted, a set of skirtings at the upper end of said duct, and a ring shaped storm hood encircling said skirtings and supported from the duct, said duct having 70 openings for the escape of air from between the skirtings.
- 75 In testimony whereof I affix my signature in the presence of two witnesses.
